UNITED STATES PATENT OFFICE.

PLINY F. HODGES, OF OLD OFFICE, VIRGINIA.

ROTARY ENGINE.

No. 906,424.

Specification of Letters Patent.

Patented Dec. 8, 1908.

Application filed August 12, 1907. Serial No. 368,239.

To all whom it may concern:

Be it known that I, PLINY F. HODGES, residing at Old Office, in the county of Goochland and State of Virginia, have invented a new and Improved Construction of Rotary Engine, of which the following is a specification.

This invention relates to rotary engines and has for its purpose to provide an improved means of utilizing the expansive force of steam in rotary engines, and it consists in parallel steam passageways between the inlet and exhaust ports and valve mechanism operating to admit and cut off the steam to said passage ways alternately, so that the initial pressure from the boiler will be applied to one of said passages while the expansive force of steam is operating in the other passage way.

20 In its more subordinate features, my invention consists in certain details of construction and peculiar combination of parts, all of which will be hereinafter fully described, specifically pointed out in the appended claims and illustrated in the accompanying drawings, in which:

Figure 1, is a perspective view of my improved construction of rotary engine. Fig. 2, is a vertical, longitudinal section thereof. Fig. 3, is a horizontal section of the casing, the rotary piston or runner being omitted. Fig. 4, is a plan view of the rotary piston or runners. Fig. 5, is a perspective view of the rotary valve.

35 In the practical arrangement of my invention, the same is arranged as shown in Figs. 1 to 4 inclusive, and comprises a circular casing 1, which rises vertically from the base or foundation 10 integral with the casing and 40 suitably flanged whereby it can be conveniently and solidly secured to a floor or other support.

Within the casing is rotatably mounted the piston 2, which is keyed to the shaft 4 that journals in hub bearings 5^a—5^a on the cap plates 5 that form the end closures for the casing 1, to which they are held, steam tight, by the cross bolts 6—6, as clearly shown in the drawings.

50 The cylinder casing 1 has centrally disposed exhausts x—x that are transversely disposed and discharge into a central exhausting port x', and at one side the said casing has a pair of transverse inlets 70^a—70^a 55 that discharge into the casing and which communicate with a single valve chamber 7

in which is rotatably mounted the valve 8 and with which the feed pipe from the boiler connects.

The valve 8, the detailed construction of which is shown in Fig. 5, is formed with a central annular steam space 8^a and at each end with a number of equi-distantly spaced channels 81 that extend in the longitudinal axis of the valve and an equal number of cut offs 82, said cut offs and the channels in the opposite ends of the valves being alternately arranged whereby to provide for a proper coöperation of the valve with the steam passages in the casing and particularly for admitting the steam intermittently and alternately through the feed ports or inlets 70^a—70^a as best shewn in Fig. 3.

The rotary piston 2 has its peripheral faces provided with two sets of parallelly disposed, but alternately arranged radial abutments 2^a, nine being shown in the drawings, that are joined by a series of peripheral passage ways or pockets 2^b that gradually but uniformly increase in depth 50 in the forward direction, that is, in the direction of rotation of the piston, for reasons presently explained.

The two sets of passage ways or pockets in the manufacture of the piston, are cored out 55 and the said two sets form, as it were, a continuous row of steam passages that are interrupted at predetermined intervals by the abutments 2^a and the said pockets or passage ways, as will be best seen from Fig. 4, do 60 not extend entirely across the piston faces but are stopped short of the ends and of each other whereby to provide inclosure portions 2^c and the central closure portion for the pockets or ways to hold the steam from passing against the end caps 5—5, the said two sets of pockets being of a width equal that of the length of the steam inlets 70^a in the bottom of the casing.

The circular casing has a series of annularly disposed radial abutments 3^a that extend crosswise the distance equal the width of the two sets of pockets or passage ways on the piston and the said abutments 3^a gradually decrease in depth from the infeed end to 100 the exhausting end of the casing, and they are joined by a series of longitudinally extending pockets 30 that gradually decrease in depth from the infeed to the exhaust side, as clearly shown in Fig. 2, from which it will 105 also be noticed that the ends of the pockets in the casing are closed by the solid portions

30^a of the casing, so as to hold the steam from passing endwise out of the said pockets 30—30.

By arranging the pockets or steam passages on the piston and on the casing in the manner shown and described, the space between the casing wall and the piston is most restricted at the infeed end and is of gradually increasing area toward the exhausts *x*, 10 whereby to provide for taking proper care of the expansive force to prevent any back lash or cushioning of the said force, since by reason of the gradually increasing depth of the casing surfaces practically all of the back 15 pressure of the explosive force is taken up by the said abutments, thereby causing the said expansive force to exert a maximum pressure against the abutments on the down-going side of the piston.

20 It will be noticed that by the peculiar construction and relative arrangement of the pockets or steam passages on the piston and the opposing casing wall, that at intervals the steam after the infeed is cut off is pocketed, the times of which is regulated by the number of pockets or abutments formed on the steam engaging faces of the casing and the piston and by reason thereof the expansive force is repeatedly utilized on the piston 25 as the live steam impulses are intermittently admitted into the restricted space between the piston and casing, the live steam impulses being regulated by the number of cut offs and feed channels formed in the rotary 30 controlling valve. Again, the valve mechanism is of such character that it provides for practically continuous live steam impulses against the piston, by reason of first charging against the abutments at one side 35 of the said piston and then against the abutments at the other side thereof, as well as the continuous use of the expansive force, since the correlation of the pockets in the piston, the steam inlet, the pockets in the casing are 40 so combined that at predetermined times the live steam impulses is either at one side of the rotary piston or at the other side, while the expansion of the prior charge is exerting itself on the down-going side of the piston, 45 such operation not alone rendering the engine one of high efficiency and speed, but also overcoming the sudden jerks and jars usually found in rotary engines. Furthermore, by reason of the gradually increasing depths of 50 the pockets in the piston peripheries and the gradually decreasing depths of the pockets in 55

the chambers, the expanding force of the steam is always directed against the piston abutments forwardly and tangentially with respect to the piston axis, thus insuring a 60 maximum energy from a minimum expense of steam power.

While I have shown the piston with nine radial abutments and pockets, I desire it understood that the said number, as also the 65 number of pockets and abutments on the piston chamber may be increased or diminished and the valve may have a greater or less number of properly spaced cutoffs and steam channels without departing from my 70 invention or the scope of the appended claims.

Having thus described my invention, what I claim and desire to secure by Letters Patent, is:—

75 1. In a rotary engine, the piston and casing therefor, comprising two series of annular abutments and pockets in the casing, two series of peripheral pockets and abutments encircling the piston, in co-operation with the 80 annular abutments and pockets, so as to form parallel steam passageways from the inlets to the exhausts, and a valve operating to admit and cut off the steam to and from the said passageways alternately, so as to apply 85 live steam impulse direct from the boiler to one of the passageways as the expansive force of the cut off steam is applied in the other passageway.

90 2. In a rotary engine, separate steam passages parallelly and alternately arranged between the inlets and exhausts the said passages consisting of a number of gradually expanding steam pockets and abutments, a casing therefor having pockets and abutments for co-operating with the said steam passages and a valve mechanism operating to admit and cut off the steam to the said passages alternately so as to apply live steam impulse direct from the boiler to one of the 95 100 passageways as the expansive force of the cut off steam is applied in the other passageways and a valve operating to admit and cut off the steam to said passages, alternately whereby to apply live steam impulse direct 105 from the boiler to one of the passageways as the expansive force of the cut off steam is on the other passageways.

PLINY F. HODGES.
